GRINDING MACHINE

Raymond H. Cramer, Newark, N. J., assignor to
 General Motors Corporation, Detroit, Mich., a
 corporation of Delaware

Application June 16, 1936, Serial No. 85,540

17 Claims. (CL 51—236)

This invention relates to grinding machines and methods and comprises all of the features and aspects of novelty herein disclosed. An object of the invention is to provide a precision grinding machine for grinding the bore of a hollow work-piece concentric with a contoured or tapered peripheral surface, said bore also being ground perpendicular to the ends of the piece. Another object is to provide improved means for preventing endwise shifting of a work-piece during grinding with provision for accurately locating the piece endwise especially when the piece is externally tapered or otherwise contoured. Another object is to provide improved means for gauging the bore of a hollow work-piece, discharging grit from the piece, and shielding the bearings for the gauge and the end thrust member. Another object is to provide improved work supporting wheels which have replaceable work engaging surfaces for contoured work-pieces. Still another object is to provide an improved method of grinding the bore of a hollow work-piece whose outer periphery is tapered or contoured.

To these ends and also to improve generally upon devices of this character, the invention consists in the various matters hereinafter described and claimed. In its broader aspects, the invention is not necessarily limited to the specific construction selected for illustrative purposes in the accompanying drawings in which:

Fig. 1 is a plan view of the machine, some parts being broken away and shown in axial section and the upper idler wheel being removed.

Fig. 2 is a front elevation of the head which supports the gauge and the thrust member, a portion of the base being broken away and in section.

Fig. 3 is a cross section on line 3—3 of Fig. 2.

Fig. 4 is an end elevation of the machine.

Fig. 5 is an enlarged sectional view of the mounting for the upper idler wheel.

The numeral 10 indicates a base plate having pads to which are screwed projecting lugs or feet 12 on a head 14 which forms a journal support for a rotary spindle 16. The spindle has a driving pulley 18 at one end and its other end is tapered to detachably receive a hub 20 fastened to the spindle by a circular clamping plate or washer 22 and a screw bolt 24. The hub 20 is externally recessed at its outer end to provide a shouldered seat for a flange or work engaging ring 26 which is fastened to the hub by screw bolts 28. The periphery of the ring 26 is tapered, preferably being transversely convex as at 30

to conform to the concave raceway surface of a race ring R or similar hollow work-piece. The ring 26 constitutes a regulating wheel which controls the rotation of the race ring R while the latter is internally ground by a grinding wheel G which is indicated by broken lines. The wheel G is adapted to be reciprocated and to be fed horizontally against the bore of the race ring at a point directly opposite to the surface 30. As will appear there are two other work-supporting wheels or flanges engaging the raceway surface and a thrust member which engages the end surface of the race ring to resist the axial pressure of the race ring induced by the angular disposition of the contoured engaging surfaces.

Projecting upwardly from the head 14 are standards 38 carrying a bracket 40 in which a rock shaft 42 is journalled for rocking movement. Projecting forwardly from the rock shaft is a pair of arms 44 and 45 connected together by a housing 46 which encloses a flange or work engaging ring 50 having a convex surface 52 conforming to the raceway surface. As shown in Figure 5 the ring 50 abuts at one end against a shoulder 54 on a hub sleeve 56, a nut 58 detachably holding the ring on the sleeve. The sleeve is journalled for rotation on a pair of spaced ball bearings of different sizes. The larger bearing 60 has its outer race ring engaging an internal shoulder in the hub sleeve and held therein by washers 62 backed up by a ring nut 64. The inner race ring of the bearing is held by washers 66 backed up by a nut 68 on an inner sleeve 70. The washers 62 and 66 have thin flanges which interfit with one another to form a labyrinth seal. The inner race ring of the bearing 60 is clamped against a spacing sleeve 72 which abuts against the inner race ring of a second ball bearing 74, the inner race ring abutting at one end against washers 76 which engage a flange 78 on the inner sleeve 70. The outer race ring of the bearing 74 is slidably mounted in the hub sleeve and the latter is closed by washers 80 clamped against an internal shoulder by a ring nut 82. The washers 76 and 80 have interfitting flanges to form a labyrinth seal.

The outer race ring of the bearing 74 is urged axially by spring pressure to preload the bearings and prevent play. A thick slide ring 84 engages the outer race ring and is provided with a series of axial sockets for coil springs 86 which also engage a series of sockets in a ring 88 which abuts against the outer race ring of the larger bearing 60. In order to limit the tendency to separate the bearings, as when the latter are

removed from the hub sleeve, screws 90 are threaded in the ring 84 and are slidable in the ring 88, the heads of the screws being contained in recesses of the ring 88 and acting as stops.

5 The inner sleeve 70 is supported by a shaft 92 having at one end a ball segment 94 contained in co-operating socket plates 96 and 98, the former being flanged and engaging an opening in the arm 45 and the socket plate 98 being threaded into the socket plate 96. At the other end, the shaft 92 has a thimble 100 secured by a screw 102. The thimble has clearance in an opening of the arm 44 and its opposite sides are flattened and engaged by set screws 104 which are arranged in pairs and radially mounted in the arm. By means of the screws 104 the shaft 92 and the hub sleeve can be tilted with respect to the other wheels so that, when the hub sleeve carries a cylindrical wheel or roller, cylindrical work will be urged in an axial direction against a thrust plate. In use, the work engaging ring 50 is pressed downwardly by a suitable spring to urge the work piece against the regulating wheel and a supporting idler wheel which will now be described.

25 A flange or work engaging ring 110 is detachably held by a ring nut 112 against an external shoulder on a hub sleeve 114. This hub sleeve is journalled for rotation in antifriction bearings 30 which are preferably constructed in the same way as the bearings shown in Fig. 5 for the work engaging ring 50. The inner sleeve 70, however, instead of being mounted on a through shaft such as 92 in Fig. 5, is mounted upon a pair of individual stub shafts 116 projecting towards one another from half round sockets 117 in a pair of spaced standards 118. The outer end portions of the studs are slabbed off or flattened at one side and clamped in adjusted position to the 40 standards by bolts 119. The heads of screws 120 overlap the ends of the shafts and provide for adjusting the flange 110 into accurate alignment with the other work-engaging flanges 26 and 50. By the foregoing construction the bolts 119 may 45 be removed to permit removal of the work engaging ring 110, hub sleeve 114 and its entire bearing structure without disturbing those bearings. The standards 118 are carried by a slide 122 having ways 124 (Fig. 4) slidable on inclined ways 126 carried by the base plate 10. The slide has 50 a tongue provided with a tapped opening for an adjusting screw 128 which is journalled for rotation without endwise movement in a plate 130 attached to the front of the base plate 10, the screw being turned by a hand wheel 132. To firmly hold the slide in position after it has been adjusted, a side clamping plate 134 has a lip which is forced against a bevelled side of the slide by a bolt 136.

60 The machine also carries a supporting structure having a gauge and a thrust plate which is provided with a thrust bearing to resist the axial component of pressure exerted on the contoured work-piece by the contoured work-engaging flanges which diverge in one direction to form a tapered work receiving space. A swivel plate 140 has a pivot stud 142 threaded into the base plate to permit adjustment of the swivel plate and clamping of the latter by bolts 144. To get 65 an accurate adjustment of the swivel plate so that the gauge will line up axially with the bore of the work piece, one end of the swivel plate has a lug 146 projecting between a pair of upright studs 148 carrying adjusting screws 150 engaging opposite sides of the lug. Fastened by screws

70 to the swivel plate is a supporting plate 152 having dove-tailed ways for a cross slide 154 which is adjustable from front to rear by a screw 156 threaded in the cross slide and journalled for rotation without endwise movement in a vertical plate 158 attached to the front of the supporting plate 152. The slide 154 carries a gauge head 160 in which a sleeve and a gauge rod are mounted for rotation, the gauge rod also being reciprocated in the sleeve. The cross slide adjusts the gauge 10 head into concentricity with the work.

75 Within each end of the head 160 is a raceway sleeve 162 and an end ring 164, a ring nut 166 being threaded in the head against the raceway sleeve and serving as the end ring for a series 15 of antifriction bearing rollers 168. Journalled for rotation in these bearings is a spindle in the form of a sleeve 170 having one end provided with a threaded portion receiving a hollow thrust member 172 having an inwardly projecting stop flange 174. The thrust member has holes 175 to facilitate cooling and removal of sludge by centrifugal action. It carries a skirt or shield 176 surrounding the adjacent end of the head 160 while its outer end carries a thrust ring 178 detachably 25 secured thereto by screws. The thrust ring has a tapered annular flange 179 with an abutment face which is ground perpendicular to its axis and is adapted to engage the end face of the raceway sleeve R to prevent axial movement of the race 30 ring. A shield 180 has an axially projecting flange engaging the interior of the stop flange 174 and abutting at its end against a bearing sleeve 182 in a counterbore of the rotary sleeve 170. Slidably mounted in the bearing sleeve 182 35 is a hollow gauge rod 184 at the inner end of which is a plate 186 having an axially projecting shield or skirt 188 overlapping the shield 180. The shield enters the thrust member and terminates in a flange to sling coolant through the 40 openings 175. Next to the plate 186 is a pair of gauges 190 held by a hollow, headed screw 192 threaded in the end of the rod and clamping the gauges and the plate 186 to the end of the rod. These gauges differ slightly in their external dimensions and are adapted to successively enter 45 the bore of the race ring as the latter is being internally ground, the gauges being intermittently thrust against the end of the piece during the grinding operation and controlling the grinding operation when they enter the work in a manner well understood in the art. Cooling fluid enters 50 the work through the gauge rod and the hollow screw and carries the sludge out through the openings 175 by centrifugal action, thus protecting 55 the bearing 182 and preventing the sludge from packing behind the gauges.

60 The other end of the rotary sleeve 170 has a bearing 200 for the gauge rod 184 on which a hub member 202 is fastened by a set screw 204. The hub member carries a flange or shield 206 and is held for rotation with the sleeve 170 by a rod 208 carried by the hub and projecting into an axial hole in the sleeve, the rod being freely 65 slidable in the hole to allow sliding of the gauge rod. Threaded on the exterior of the head 160 is an adjusting nut or sleeve 210 having an internal flange 212 next to a thrust ring 214 of a ball thrust bearing 216. An opposed thrust ring 218 is clamped against a shoulder in the sleeve 70 210 by a ring nut 220. The thrust ring 214 is clamped against a shoulder of the rotary sleeve 170 by an axially projecting flange on a nut 222. Thus the end thrust of the work piece against the thrust ring 178 is transmitted through the spin- 75

idle or sleeve 170 and resisted by the antifriction thrust bearing. An accurate endwise adjustment of the thrust ring is afforded by the threaded sleeve 210 which acts as an adjustable extension of the head 160 and will shift the thrust plate 218 axially with respect to the gauge head, such adjustment being maintained by a lock nut 223. The above mentioned shield 206 overlaps the threaded sleeve 210 and protects the thrust bearing.

On the top of the head 160 is an oil cup 230 to provide for lubrication of the bearings 168, holes 231 in the sleeve 170 conducting oil to bearing sleeves 182 and 200. A locking pin 232 is adapted to be projected radially into a hole 234 (Fig. 3) to lock the rotary sleeve 170 against rotation as when applying or removing the threaded thrust sleeve 172. The locking pin carries a little latch pin 236 normally engaging shallow recesses in a pair of lugs 238 projecting upwardly from the head. A knob 240 is secured to the upper end of the locking pin whereby the latter may be elevated to remove the little latch pin 236 from its recess in the lugs and turned 90° so that the latch pin will enter a cross recess 242 between the lugs, thus letting the locking pin down into the hole 234.

The three contoured work supporting rings or flanges and the thrust member are mounted to rotate on parallel axes and together with the end face of the thrust member are ground on the machine at one setting to insure accurate location of the work for grinding. A grinding wheel (not shown) is first given the transverse inclination or contour desired for the work by suitable dressing mechanism and placed on the wheel spindle. It is then fed against the flange or ring 26 to shape the latter. The lower flange or ring 110 which can be moved up to the grinding wheel by the inclined slide 122 is then ground by feeding the grinding wheel rearwardly. Then the upper work supporting flange or ring 50 is swung down and similarly ground. The face 179 of the thrust ring 178 is ground flat and perpendicular to its axis of rotation by the end of the grinding wheel, the swivel plate 140 providing for adjustment of this axis into parallelism with the other axes. This truing of all the work engaging members on the machine at one setting insures a perfect set-up for concentricity, squareness and alignment in grinding the bore of the race ring R or other contoured work-piece. For work-pieces which have a different contour, the work-engaging rings or flanges 26, 50, and 110 are readily removable for replacement by others all without disturbing the hub structure or their alignment.

In operation, the race ring R is rotatably supported with its contoured surface against the three rings or flanges, the end of the race ring abutting against the face 179 which takes the reaction or endwise component of pressure due to the inclination of the contoured surfaces. This face is accurately adjusted endwise of the work by the threaded sleeve 210 which controls the position of the thrust bearing 216 and the sleeve 170. The work is thus accurately located and when the grinding wheel R is fed against the bore and reciprocated therein, the bore is ground concentric with its periphery and perpendicular to the ends of the work.

I claim:

1. In a machine of the character described, means for supporting and rotating a round work-piece, an end thrust member adapted to engage one end of the work-piece to locate the latter

axially and to resist endwise movement thereof, journal bearings for rotatably supporting the end thrust member, a thrust bearing for preventing endwise movement of the end thrust member, a head for supporting said end thrust member and its bearings independently of said work supporting and rotating means, and means for axially shifting the thrust bearing and the end thrust member with respect to said head; substantially as described.

2. In a machine of the character described, means for supporting and rotating a round work-piece, a head, a rotatable hollow spindle journaled in the head and having an end thrust member adapted to engage one end of the work piece to resist endwise movement thereof, a thrust bearing reacting between the spindle and the head, and means for shifting the spindle and its thrust bearing axially with respect to the head; substantially as described.

3. In a machine of the character described, means for supporting and rotating a round work-piece, a head having journal bearings, a rotatable spindle journaled in the bearings and adapted to shift axially therein, the spindle having a thrust member at one end adapted to engage the end of the work-piece, the head having an adjusting member threaded thereto, and an antifriction thrust bearing housed in the adjusting member and reacting between the adjusting member and the other end of the spindle; substantially as described.

4. In a machine of the character described, means for supporting and rotating a hollow work-piece, a head, a rotatable sleeve journaled in the head independently of the supporting and rotating means and having an end thrust member adapted to engage one end of the work-piece, a thrust bearing reacting between the sleeve and the head, a rod slidable in the sleeve, and a hub member on the rod and having a flange overlapping the thrust bearing; substantially as described.

5. In a machine of the character described, means for supporting and rotating a hollow work-piece, a rotatable sleeve mounted independently of the supporting and rotating means and carrying an end thrust member adapted to engage one end of the work-piece, a gauge rod slidably mounted in the sleeve and having a gauge adapted to enter the work piece, a hub member secured to the gauge rod at one end of the sleeve, a pin carried by one of the last named parts and entering axially into a hole in the other part, and the hub member having a shield projecting around the sleeve; substantially as described.

6. In a machine of the character described, wheels for peripherally supporting and rotating a hollow work-piece, a hollow end thrust member adapted to engage one end of the work-piece, means for conducting coolant to the interior of the work-piece, and said end thrust member having openings to discharge the coolant; substantially as described.

7. In a machine of the character described, wheels for peripherally supporting and rotating a hollow work-piece, a spindle having a hollow end thrust member adapted to engage one end of the work-piece, means for conducting coolant to the interior of the work-piece, the thrust member having openings, and a rotatable shield extending into the thrust member to discharge the coolant through said openings; substantially as described.

8. In a machine of the character described, wheels for peripherally supporting and rotating

a hollow work-piece, a rotatable sleeve having a hollow end thrust member adapted to engage one end of the work-piece, the thrust member having openings, a hollow rod extending through the sleeve to conduct coolant to the interior of the work-piece, and a shield carried by the rod and entering the hollow thrust member; substantially as described.

9. In a machine of the character described, 10 wheels for peripherally supporting and rotating a hollow work-piece, a rotatable sleeve having a hollow end thrust member adapted to engage one end of the work-piece, the thrust member having openings, a rod extending through the sleeve, a 15 shield carried by the sleeve, and a shield carried by the rod, said shields overlapping one another inside the thrust member; substantially as described.

10. In a machine of the character described, 20 wheels for peripherally supporting and rotating a hollow work-piece, a rotatable sleeve having a hollow end thrust member adapted to engage one end of the work-piece, the thrust member having openings, a gauge rod extending through the 25 sleeve and having a gauge adapted to enter the work-piece, means for conducting coolant to the interior of the work-piece, and a plate carried by the gauge rod and having a shield entering the hollow thrust member; substantially as described.

30 11. In a machine of the character described, wheels for peripherally supporting and rotating a hollow work-piece, a rotatable sleeve having an end thrust member adapted to engage one end of the work-piece, a head having bearings for rotatably supporting the sleeve, and a gauge rod slidably mounted in the sleeve and having a gauge adapted to enter the work-piece; substantially as described.

12. In a machine of the character described, 40 wheels mounted to rotate on parallel axes to peripherally support and rotate a round work-piece, an end thrust member adapted to engage the end of the work-piece, a swivel plate having means to rotatably support the end thrust member, and 45 means for swivelling the plate to locate the axis of the end thrust member with respect to the wheel axes; substantially as described.

13. In a machine of the character described,

wheels mounted to rotate on parallel axes to peripherally support and rotate a round work-piece, an end thrust member adapted to engage the end of the work-piece, a head having bearings for rotatably supporting the end thrust member, a 5 swivelling support for the head, and means for angularly adjusting the support to locate said bearings in parallelism with the axes of the wheels; substantially as described.

14. In a machine of the character described, 10 means for rotatably supporting a round work-piece and comprising a plurality of wheels and an end thrust member, the wheels and the thrust member being rotatable on parallel axes and the wheels being spaced angularly about a central 15 work receiving space, and the peripheries of the wheels converging in one direction to urge the work-piece against the thrust member; substantially as described.

15. In a machine of the character described, a 20 work head comprising a plurality of angularly spaced work supporting surfaces which incline with respect to a central axis to exert radial and axial pressure against the similarly inclined periphery of a work-piece interposed between them, 25 and a thrust member rotatable in line with said axis and engaging the end of the work-piece to prevent axial movement thereof; substantially as described.

16. In a machine of the character described, a 30 work head comprising a plurality of rotatable wheels angularly spaced about an axis and having their peripheral surfaces inclined to said axis to form a tapered work-receiving space for an externally tapered work-piece, a spindle rotatable 35 in line with said axis, and a thrust member carried by the spindle and having a thrust face normal to said axis to engage the end of the work-piece to hold the latter in contact with the wheels; substantially as described.

17. In a machine of the character described, a work-head comprising a plurality of hub members rotatable about parallel axes, the hub members having external seats, and flanges secured on said seats and having peripheral surfaces which 45 are similarly contoured and inclined with respect to said axes; substantially as described.

RAYMOND H. CRAMER.
